UNITED STATES PATENT OFFICE.

ERWIN CALDWELL, OF BIRMINGHAM, ALABAMA, ASSIGNEE TO PERRY CALDWELL MANUFACTURING COMPANY (INC.), A CORPORATION OF ALABAMA.

BLOW-OFF DEVICE FOR STEAM BOILERS.

Application filed January 21, 1925. Serial No. 3,818.

The present invention relates to improvements in cleaning devices for steam boilers, and the primary object of the invention is to provide means whereby the boiler will 5 be relieved not only of sediment and scale-forming substances which are in suspension in the boiler water, but which is capable of removing from the boiler scale-forming substances, such, for example, as salts and similar 10 soluble matters which are in solution in the boiler water and, hence, are incapable of removal from the boiler water by boiler cleaners of the kinds heretofore proposed which depended upon filtration, precipitation 15 or settling of the scale-forming substances.

According to the present invention, water is continuously blown off from the boiler, from a point below the water line thereof 20 and preferably at or near the bottom of the boiler where the sediment accumulates and the impurities or scale-forming substances are concentrated, under the automatic control of an orifice or nozzle, the size of which 25 is proportioned in accordance with the capacity of the boiler and the pressure at which it is operated, and the water thus blown off is discharged into a sewer or is otherwise discarded. The salts or other scale-forming substances in solution in the boiler water are thereby removed from the boiler, and, hence, they cannot become concentrated 30 as the result of evaporation to form scale or deposits on the heating surfaces of the boiler. The removal of the boiler water containing scale-forming substances in solution therein also removes from the boiler scale-forming matters in suspension therein.

By continuously withdrawing water from 40 the boiler, and especially from the lower portion thereof, through an orifice or nozzle of appropriate size, the boiler water is kept substantially clear of scale-forming substances, including those in solution as well as those in suspension, and these substances are removed from the boiler automatically 45 or without requiring the attention of an attendant.

To these and other ends, the invention consists in certain improvements and combinations and arrangements of parts, all as will be hereinafter more fully described, the features of novelty being pointed out particularly in the claims at the end of the specification.

In the accompanying drawing:

Figure 1 is a sectional view of a boiler blow-off device constructed in accordance with the present invention; and

Figure 2 is a diagrammatic view showing 60 the blow-off device operatively connected to a steam boiler.

Similar parts are designated by the same reference characters in the several views.

The present invention is applicable generally to steam boilers of various types where it is desirable or necessary to prevent the accumulation and deposit of scale-forming substances therein. The preferred embodiment of the invention is shown in the 70 accompanying drawing and will be herein-after described in detail, but it is to be understood that the invention is not restricted to the precise construction shown, as equivalent constructions are contemplated, and such will be included within the 75 scope of the claims.

In the present instance, 1 designates a portion of a steam boiler which may be of any of the types known or used, and 2, Fig. 80 1, or 2^a, Fig. 2, represents a blow-off pipe which leads from the bottom or lower portion of the boiler, and it may be the blow-off pipe which has heretofore been used generally on steam boilers for the purpose of 85 blowing off boiler water therefrom, it having been the previous practice to blow off boiler water through such a blow-off pipe periodically by opening a valve attached to the blow-off pipe. However, the discharge of boiler water at intervals, as has been the usual practice, does not effectively prevent the deposit of scale in the boiler, as during the intervals between the blow-off operations, the scale forming impurities collect or become concentrated in the boiler water, due to the evaporation of the water, and a considerable amount of these impurities will become deposited and will form scale in the boiler notwithstanding the periodic blowing off of water therefrom, as has been heretofore practiced. It has been proposed to withdraw water from the boiler, and after subjecting the withdrawn water to filtration, precipitation or settling, to return such water to the boiler, but such methods would not be effective to prevent the formation of scale in the boiler as the salts or other soluble scale-forming substances

105

115

are in solution in the water, they cannot be

separated therefrom by the methods previously proposed, and they would be reintroduced into the boiler with the water returned thereto.

5 The present invention provides a boiler cleaner which comprises a blow-off device which operates continuously and automatically to discharge water from the bottom or lower portion of the boiler where sediment or substances in suspension collect and impurities or substances in solution in the water are concentrated. The rate of discharge of the water is regulated automatically by an orifice or nozzle, the size of 10 which is properly proportioned to suit the steaming capacity of the boiler and the pressure at which it is operated. This orifice or nozzle receives the boiler water at or substantially at boiler pressure and it discharges it into a sewer or other means of 15 disposal, the difference of pressure at the inlet and discharge sides of the orifice being constant or substantially so and sufficient to insure the continuous and effective discharge 20 of water from the boiler at a rate which is regulated automatically according to the size of the orifice and pressure at which the boiler is operated. By withdrawing boiler water in this manner, accumulation and 25 deposit of scale-forming substances in the boiler is prevented as the salts or other soluble scale-forming substances which are in solution in the water, as well as the sediment and other impurities which are in suspension 30 in the water are continuously withdrawn from the boiler so that accumulation and concentration of these scale-forming substances, due to evaporation of the water, cannot occur, and as the water thus withdrawn from the boiler is discharged into a 35 sewer or otherwise discarded, there is no opportunity for the return of the soluble impurities to the boiler.

40 The device, in the embodiment of the invention herein shown, comprises a receptacle 3 which may be cylindrical or otherwise formed in cross-section and is elongated vertically to provide a chamber 4 of appropriate height. The top and bottom of the receptacle are closed and the receptacle is so constructed that it is capable of withstanding boiler pressure. An inlet pipe 5 is threaded or otherwise fitted into the upper head of the receptacle and projects downwardly within the latter to a point near its bottom, the lower end of this inlet pipe being open. The upper end of the inlet pipe is suitably connected to the boiler or boilers with which the device is used. As 45 shown, the upper end of the inlet pipe has attached thereto exteriorly of the receptacle 3 a pipe fitting 6, this fitting comprising preferably a T, the upper end of which is closed by a removable plug 7 which is in alignment with the inlet pipe 5, and a pipe

8 is attached to the branch connection of the T, the opposite end of this pipe being connected to the branch connection of a T 9, the upper end of which is attached to a gate or other suitable valve 10, which latter, in turn, is connected to the boiler or to the blow-off pipe 2 or 2^a thereof. A clean-out plug 11 is preferably fitted into the lower end of the T 9 opposite to the valve 10. A nozzle 12 is threaded or otherwise fitted into the upper head of the receptacle and it projects downwardly into the upper end of the chamber 4, the nozzle having a vertically, axially elongated orifice 12^a which has a cross-section which is appropriately proportioned to give the desired rate of discharge or continuous blow-off of the boiler water to suit the steaming capacity of the boiler. The nozzle 12 is connected exteriorly of the receptacle 3 to suitable piping which leads to a sewer or other point of disposal. As shown, the pipe T 13 is connected at one end to the nozzle, its opposite end in line with the nozzle being provided with a clean-out plug 14, and the lateral branch of the T is connected to a pipe 15 which serves to conduct the water discharged from the nozzle to the sewer or point of disposal. The pipe 15 is preferably open at its end to the atmosphere so that back pressure on the nozzle is substantially eliminated. Suitable means is provided for discharging sediment which may collect in the bottom of the chamber 4 of the receptacle, a discharge valve 16 being shown for this purpose, the valve being connected to the lower head of the receptacle.

50 The mode of operation of the blow-off device is as follows: When the boiler has been steamed up, the drain valve 16 is closed, and the valve 10 is opened, and the latter valve remains open during the operation of the boiler. The pressure in the boiler forces the boiler water from the bottom or lower portion thereof out through the valve 10, pipe 8 and inlet pipe 5 into the lower portion of the chamber 4, and this water rises in the latter chamber and discharges through the contracted orifice 12^a of the nozzle 12 into the discharge pipe 15 through which it is conducted to the sewer or place of disposal. The blow-off of the boiler water takes place continuously during the operation of the boiler and the rate of discharge of the water is regulated automatically by the size of the orifice of the nozzle, and, hence, the device is automatic in its operation. The continuous withdrawal of water from the bottom or lower portion of the boiler removes from the boiler any sediment and impurities which are either in solution or in suspension in the boiler water, these impurities being more concentrated in the bottom or lower portion of the boiler, and, hence, there is

no opportunity for concentration of these impurities to a degree to cause scale-forming deposit of these impurities upon the heating surfaces of the boiler. By appropriately proportioning the size of the orifice in the nozzle according to the steaming capacity of the boiler, the continuous blow-off of water from the bottom or lower portion of the boiler may take place at a rate which will substantially eliminate any substantial degree of concentration of the salts or soluble scale-forming impurities in the boiler water, and will substantially prevent accumulation of sediment or impurities in suspension in the boiler water.

The valve 16 connected to the bottom of the receptacle 3 may be opened occasionally to drain from the chamber 4 any sediment or solid impurities which may accumulate in the receptacle, and the plugs 7, 11 and 14 may be removed at any time if necessary to clean out the pipe 5, valve 10 or the nozzle 12. It will be understood that the device may be connected to serve one or more boilers, if desired, and that the device may be connected in different ways to the boiler or boilers or to a blow-off pipe connected thereto. By locating the orifice device or nozzle in the upper portion of a chamber which receives the boiler water, it is protected from clogging by sediment or solid particles that may be carried over by the water, as such sediment or solid particles will be trapped in the lower portion of the chamber, and they may be drained off by occasionally opening the drain valve at the bottom of this chamber. Enlargement of the orifice under the cutting action of the water discharging therethrough is substantially avoided by axially elongating the orifice substantially to the extent shown, and clogging of the orifice by sediment is avoided, as the orifice is arranged vertically and it leads upwardly from the upper portion of the sediment intercepting receptacle.

The automatic blow-off device embodying the present invention not only prevents the formation of scale in steam boilers but it also prevents "foaming" of the water by reason of the reduction which it effects in the concentration of the matters in suspension and in solution in the boiler water. Consequently, it effects a great reduction in the loss of water which has heretofore been carried off from the boiler with the steam as the result of foaming.

I claim as my invention:-

1. A blow-off device for steam boilers comprising a receptacle having means for connecting it to receive water from the water space of a boiler, and refuse-water discharge means leading from said receptacle at a point removed from the path of the boiler water entering it and having a restricted orifice leading upwardly from the

upper portion of the receptacle for continuously discharging the boiler water received by the receptacle.

2. A blow-off device for steam boilers comprising a receptacle having means for conducting water to the lower portion thereof continuously from the lower portion of the water space of a boiler and refuse-water discharge means leading from said receptacle and having restricted orifice means leading upwardly from the upper portion of the receptacle out of the path of the boiler water entering it for continuously discharging said water therefrom.

3. A blow-off device for steam boilers comprising a receptacle having means extending to the lower portion of the receptacle for conducting water thereto continuously from a boiler and constantly open refuse-water discharge means leading from the top of said receptacle and having a restricted nozzle projecting downwardly from the top of the receptacle for continuously discharging said water therefrom at a rate determined by the size of said nozzle.

4. The combination with a steam boiler, of a blow-off pipe for continuously discharging water from the water space thereof, and constantly open refuse-water discharge means comprising a restricted downwardly directed orifice device connected to receive the water from the blow-off pipe by an upward flow of the water and operative to discharge such water continuously under the influence of the boiler pressure and at a rate determined by said orifice device.

5. A blow-off device for steam boilers comprising a receptacle having means for connecting it to receive water from the water space of a boiler, and constantly open refuse-water discharge means comprising a constantly open relatively contracted axially elongated orifice of fixed size leading from said receptacle at a point removed from the path of the water entering it from the boiler for continuously discharging the boiler water received by the receptacle at a rate determined by the size of said orifice.

6. A blow-off device for steam boilers comprising a sediment-intercepting receptacle having means for connecting it to the water space of a boiler to receive boiler water therefrom, and constantly open refuse-water discharge means leading from the top of said receptacle and having at its point of communication therewith and leading upwardly therefrom a substantially vertical relatively contracted constantly open orifice of fixed size operative to continuously discharge water from said receptacle to said discharge means and to determine the rate of such discharge.

In testimony whereof I have hereunto set my hand.

ERWIN CALDWELL.
